[57] CLAIM

The ornamental design for a toy robot convertible into a combat car, as shown and described.

DESCRIPTION

FIG. 1 is a front elevation view of a toy robot convertible into a combat car showing my new design;
FIG. 2 is a rear elevation view of the toy robot;
FIG. 3 is a right side elevation view of the toy robot, a left side elevation view being omitted which is symmetrical thereto;
FIG. 4 is a top plan view of the toy robot;
FIG. 5 is a bottom plan view of the toy robot; and
FIG. 6 is a modified form of the toy robot when converted to a combat car.

FIG. 2

FIG. 1

FIG. 3

FIG. 6

FIG. 5
